UNITED STATES PATENT OFFICE.

GEORG KRAUS, OF CLEVELAND, OHIO.

FLOUR-BIN.

No. 857,076.

Specification of Letters Patent.

Patented June 18, 1907.

Application filed April 24, 1907. Serial No. 370,000

To all whom it may concern:

Be it known that I, GEORG KRAUS, a citizen of the United States of America, residing at Cleveland, in the county of Cuyahoga and State of Ohio, have invented certain new and useful Improvements in Flour-Bins; and I hereby declare the following, to be a full, clear, and exact description of the invention, such as will enable others skilled in the art to 10 which it pertains to make and use the same.

This invention relates to improvements in flour bins.

The object of this invention is to provide, in combination with a receptacle or chest, 15 having a door arranged to swing vertically, a bin having means for removably mounting it on the door of the chest so that the bin may be readily removed in order to clean or empty the same.

20 My invention therefore consists in the features of construction and combination of parts, as described in the specification, pointed out in the claims and illustrated in the accompanying drawings.

25 In the accompanying drawings Figure 1 is a perspective view of a receptacle or chest on the door of which is mounted my improved bin. Figs. 2 and 3 are sections through the bin at a right angle to each other.

30 Again referring to the drawings 1 represents a stationary receptacle or chest of the usual construction. Such chests are generally constructed of wood and are built into the pantries of houses when the houses are 35 constructed. The chests are provided with vertically swinging doors and according to the location of the chests in the pantries the doors will in some cases open to the right and in other cases the doors will open to the left.

40 The chest shown in the drawings is provided with a door 2 which opens to the left. At the top of the door 2 on the inside face thereof are secured two leaves 3 which are provided with hinge barrels 4. Across the bottom 45 of the door is secured a plate 6 which has an offset portion 7 which stands out from the surface of the door and forms a bracket. The bin for holding the flour is preferably made of sheet metal and is quadrant shaped in horizontal section having two straight sides 10 and 11 and a curved side 12. At the top of 50 each straight side of the bin near the center thereof is formed a hinge barrel, indicated by 13 and 14, of the same size as the hinge barrel on the door. At the bottom of each straight side of the bin is formed a depending

flange indicated by 15 and 16. The flanges 15 and 16 are adapted to fit into the bracket on the door. On the bottom of the bin and preferably beneath the center thereof is arranged a support or leg 17 which is provided with a roller bearing 18 which is designed to travel on the floor of the pantry. The leg 17 practically supports the weight of the bin and therefore takes the strain off of the door. 60 The bin is provided with a quadrant shaped cover 20 which is provided with hinge barrels 21 which are in all respects similar to the hinge barrels 4 on the door. Pintle pins 22 and 23 of equal cross section are provided for 65 operatively connecting the hinge member on the door to the hinge member on one of the sides of the bin and for connecting the hinge-member on the other side of the bin with the hinge member on the cover. Handles 24 70 and 25 respectively are formed on the ends of the pintles 22 and 23 so that they may easily be withdrawn from the barrels of the hinge-members.

75 By means of my invention I am able to 80 provide a bin which can be mounted upon a door which opens either to the right or to the left. This is not only a great advantage in manufacturing and marketing the bins but also makes the bins more serviceable to the 85 purchaser, for the owner of a bin on leaving a house can take the bin with him knowing that the bin will fit any door.

When the door of the chest swings to the left, as is shown in the drawing, the bin is 90 mounted upon the door as heretofore described and when it is desired to empty or clean the bin the pintle connecting the hinge-member on the bin to the hinge member on the door is withdrawn and the bin can readily be removed from the door. Now if it is necessary to place the bin upon a door which opens to the right the pintle securing the cover is withdrawn and the cover is reversed and the hinge member on the cover is connected with the hinge-member on the bin which was formerly connected with the hinge-member on the door and the hinge member on the bin which was formerly connected with the hinge-member on the cover 105 is then connected with the hinge-member on the door.

What I claim is:—

1. The combination with a chest having a door hinged to swing vertically of a hinge-member secured on the inner face of said door near the top thereof, a bracket secured

below said hinge-member, a bin, quadrant-shaped in horizontal section, a hinge-member arranged on one of the straight sides of said bin at the top thereof, a depending flange secured at the bottom of said side and arranged to fit into the bracket on the bottom of the door and a pintle operatively connecting the hinge-member on the door and the hinge-member on the bin.

- 16 2. The combination with a chest having a door hinged to swing vertically of a hinge-member secured on the inner face of said door near the top thereof, a bracket secured below said hinge-member, a bin, quadrant-shaped in horizontal section, a hinge-member arranged on one of the straight sides of said bin at the top thereof, a depending flange secured at the bottom of said side and arranged to fit into the bracket on the bottom of the door, a pintle for operatively connecting the hinge-member on the door and the hinge-member on the bin and a support secured beneath said bin on the bottom thereof and provided with roller bearings.
- 25 3. The combination with a chest, having a door hinged to swing vertically of a hinge-member secured on the inner face of said door near the top thereof, a bracket secured on said door below said hinge-member, a bin, quadrant shaped in horizontal section, a hinge-member arranged at the top of each straight side of said bin and provided with barrels of the same size as on the hinge-member on the door, a depending flange adapted to fit into the bracket on the door secured at the bottom of each straight side of said bin, a cover provided with a hinge-member corresponding to the hinge-member on the door, pintles for operatively connecting the hinge-member on one of the straight sides of the bin to the hinge-member on the door and for securing the hinge-member on the cover to the hinge-member on the other straight side of the bin and a support mounted on the bottom of said bin and provided with a roller bearing.
- 35 35 to the bottom of each straight side of the said bin, a cover provided with a hinge-member

corresponding to the hinge-member on the door and pintles for operatively connecting the hinge-member on one of the straight sides of the bin to the hinge-member on the door and for securing the hinge-member on the cover to the hinge-member on the other straight side of the bin.

4. The combination with a chest having a door hinged to swing vertically of a hinge-member secured on the inner face of said door near the top thereof, a bracket secured on said door below said hinge-member, a bin, quadrant shaped in horizontal section, a hinge-member arranged at the top of each straight side of said bin and provided with barrels of the same size as on the hinge-member on the door, a depending flange adapted to fit into the bracket on the door secured at the bottom of each straight side of said bin, a cover provided with a hinge-member corresponding to the hinge-member on the door, pintles for operatively connecting the hinge-member on one of the straight sides of the bin to the hinge-member on the door and for securing the hinge-member on the cover to the hinge-member on the other straight side of the bin and a support mounted on the bottom of said bin and provided with a roller bearing.

In testimony whereof, I sign the foregoing specification, in the presence of two witnesses.

GEORG KRAUS.
